UNITED STATES PATENT OFFICE.

CARL F. NAYER, OF CHICAGO, ILLINOIS, ASSIGNEE TO PACKERS MACHINERY & EQUIPMENT COMPANY, OF CHICAGO, ILLINOIS.

HOG-SCRAPER.

1,328,637.

Specification of Letters Patent.

Patented Jan. 20, 1920.

Application filed October 31, 1918. Serial No. 230,447.

To all whom it may concern:

Be it known that I, CARL F. NAYER, a citizen of the United States, residing at Chicago, in the county of Cook and State of Illinois, have invented a certain new and useful Improvement in Hog-Scrapers, of which the following is a full, clear, concise, and exact description, reference being had to the accompanying drawings, forming a part of this specification.

My invention relates to hog scrapers and has for its object the provision of a new and improved machine of this character in which the number of appliances necessary to completely and thoroughly dehair and polish a hog has been reduced to a minimum.

In a specific form of the invention I utilize a plurality of dehairing devices which in general are disk-like in shape carrying dehairing elements upon one face of the disk. These elements are so placed in the machine that they serve the dual purpose of supporting and dehairing the hog.

My invention further contemplates in one of its forms suitable means for rotating the hog while the dehairing devices are operating upon it. These means for rotating the hog may serve at the same time for ejecting the hog from the machine when the dehairing and polishing operation has been completed.

I will describe my invention more in detail by referring to the accompanying drawings, in which—

Figure 1 is a side view of my improved machine;

Fig. 2 is a sectional view on line 2—2 of Fig. 1, the conveyer element being omitted for the sake of clearness, and

Fig. 3 is a top view of the machine.

Figs. 4 and 5 are respectively front and side views of one of the dehairing devices.

The machine of my invention comprises a suitable framework having the legs 10 suitably placed adjacent a scalding tank 11. The framework is preferably rectangular and includes the top cross pieces 12 which project to the right, as shown more clearly in Fig. 1, to support certain parts of the mechanism, as will presently appear. Further cross-pieces 13 are placed centrally at the sides of the machine. The framework is also suitably held together longitudinally by

angle irons such as 14 and 15. Diagonal end pieces 16 are shown provided to strengthen the machine and to support a channel iron 17 which, as will presently appear, carries the bearings for the dehairing devices.

There are four dehairing devices 18, 19, 20 and 21. These devices include a disk-like structure preferably in the form of a circular casting having depressions 22, and along one of the side walls of each of which depressions the dehairing elements 23 are secured preferably by being bolted to the wall of said depression by the bolts 24 (Fig. 1). Each dehairing device is mounted upon a shaft 25, which shaft is carried in suitable bearings provided upon the channel iron 17 and the extremity of each shaft is provided with a bevel gear 26. These gears in turn mesh with cooperating bevel gears 27 carried by a shaft 28, which shaft is driven directly by the pulley 29. In the particular structure herein disclosed the arrangement of the bevel gears 27 is such that two of the dehairing devices rotate in one direction, while the other two dehairing devices rotate in the opposite direction. In this manner the hog is held in its central position and is not carried off by the action of the beaters or dehairing elements carried by the dehairing devices. The hog rests directly upon the dehairing devices. The space between the dehairing devices may be suitably filled in with any suitable material such as a casting or otherwise, not shown herein however, so as to prevent the legs of the animal from falling in between any two dehairing devices. A similar form of such filler plate is shown in my co-pending application Serial No. 236,106, filed May 23, 1918.

Adjacent the dehairing devices I provide a conveyer 30 having the angles 31, which conveyer suitably passes about sprockets 32, 33. The sprocket 33 is fixedly secured to the shaft 34, which shaft (Fig. 2) is driven directly from the shaft 28 through the interposition of the sprocket chain 35 and sprocket wheel carried respectively by the said shafts 28 and 34. The conveyer 30 which rotates in a contra-clockwise direction (Fig. 1) rotates the hog at the same time that the rotating beaters dehair and polish it. The sprocket wheels 32 are suitably mounted upon a shaft 36, which shaft is carried on the lower extremity of the

link 37. As this link 37 moves up and down, the path of the shaft 36 is regulated by its movement within the slot 38. The object of moving the shaft 36 and thus lowering the 5 left hand extremity of the conveyer (Fig. 1) is to permit the conveyer to discharge or eject the hog from the machine after the dehairing operation has been completed. The mechanism which controls this actuation 10 of the left hand extremity of the conveyer will be presently described.

The description hitherto given of the actual means which perform the dehairing and polishing operation will indicate that 15 the rotating dehairing devices not only dehair and polish the hog, but at the same time support it during this operation. It will also be apparent that there is but one gang or set of dehairing devices, by which 20 I mean that there are a plurality of similar and similarly mounted and operating dehairing devices. The words "similarly operating" however must of course include the relative opposite rotation of the dehairing 25 devices 19 and 20, for instance.

Suitable control devices now to be explained periodically lower the one extremity of the conveyer to thereby discharge the hog, and these control devices at the same 30 time control the actuations of certain instrumentalities to introduce another hog into its proper place for dehairing. The hog to be dehaired is taken from the scalding tank 11 and is deposited upon a suitable cradle 39, which cradle is pivotally supported by the hanger 40. This hanger carries at its upper 35 extremity a roller 41 to guide it in its travel within the slot 42. A link 43 is also pivotally united to the hanger and is united at its opposite extremity to a hoisting rope 44. These hoisting ropes are suitably arranged 40 and pass over a plurality of sheaves 45, as shown more clearly in Fig. 3, the extremities of the ropes being fastened to framework 46 carrying the second set of pulleys or sheaves. The framework 46 is moved to the right or left (Fig. 1) as it is desired to raise or lower the cradle 39. It will be seen 45 that a very slight movement of the framework 46 causes a movement many times multiplied of the cradle 39 due to the particular arrangement of the pulleys. The framework 46 forms part of an eccentric strap 47 which coöperates with the eccentric 50 strap 48. The eccentric 48 are mounted upon the shaft 49 and this shaft is periodically actuated whenever it is desired to introduce an undehaired hog into the machine. The shaft 49 also carries a cam 50, which cam, as 55 will presently appear, controls the up and down movement of the shaft 36. Thus, whenever the shaft 49 is rotated, the conveyer is lowered to discharge the hog from the machine at the same time that the cradle 60 39 is raised to introduce a fresh hog into

the machine. The runway or slot 42 is provided in a casting 51, suitably carried by the framework of the machine. This casting likewise carries two rollers 52 and 53 to assist in guiding the hanger 40 as it 70 moves from the position shown in full lines in Fig. 1 to its dotted position as shown in the same figure.

In order to operate the shaft 49 I provide a sprocket wheel 54, which through the 75 agency of the chain 55 is driven from the sprocket wheel 56. This sprocket wheel 56 on the shaft 34 is adapted for connection with said shaft through the agency of the coupling 57. This coupling 57 is controlled 80 by the handle 58. Thus, whenever the dehairing operation of a hog within the machine has been completed the operator directs the handle 58 to the right (Fig. 3), whereupon the left hand extremity of the 85 conveyer 30 (Fig. 1) is lowered at the same time that the cradle 39 is raised to deposit a fresh hog into the machine. The conveyer 30, as already explained, is continuously operated both when the hog is being discharged and when it is in the machine, as this conveyer serves to rotate the hog while it is being dehaired. The cam 50 coöperates with a suitable roller 59, which roller is carried by an arm 60 pivoted in the framework of the machine at 61. The arm 60 at its right hand extremity (Fig. 1) pivotally supports the link 37. The shape of the cam 50 is such that immediately the handle 58 is operated, the left hand conveyer extremity is lowered to discharge the hog. The conveyer remains in that position during about one-half of a revolution of the shaft 49, whereupon it is replaced in the position shown in full lines in Fig. 1 and remains 100 that way during the later revolution of the shaft 49. It will be understood that but one complete rotation of the shaft 49 is needed for introducing and discharging hogs. During the first half of the revolution of the 105 shaft 49 the cradle 39 is being raised and it is some time during the latter half of the revolution of the shaft 49 that the cradle 39 reaches the dotted position shown in Fig. 1, at which time it deposits a hog into the position where it may be dehaired by the dehairing devices and rotated by the conveyer. 110

From this description the nature of my invention will be readily clear and it will be apparent that the illustrations and description merely set forth one form of carrying out my invention. Various modifications may be made without departing from its spirit, all within the scope of the appended 115 claims:

1. In a dehairing machine of the character described, a plurality of dehairing devices each operating upon the carcass in a circular path and an inclined conveyer, said dehairing devices and conveyer being 120 125 130

mounted in a manner to support said carcass between them during the dehairing operation.

2. In a dehairing machine of the character described, a plurality of dehairing devices each operating upon the carcass in a circular path, said dehairing devices being mounted in a manner to support said carcass during the dehairing operation, certain of said dehairing devices rotating relatively in opposite directions.

3. In a dehairing machine of the character described, a plurality of dehairing devices each operating upon the carcass in a circular path, said dehairing devices being mounted in a manner to support said carcass during the dehairing operation, and means for rotating the carcass during the dehairing operation, the carcass being supported only by the dehairing devices and the means.

4. In a dehairing machine of the character described, a plurality of dehairing devices each operating upon the carcass in a circular path, said dehairing devices being mounted in a manner to support said carcass during the dehairing operation, certain of said dehairing devices rotating relatively in opposite directions, and means for rotating the carcass during the dehairing operation.

5. In a dehairing machine of the character described, a plurality of dehairing devices each operating upon the carcass in a circular path, said dehairing devices being mounted in a manner to support said carcass during the dehairing operation, means for rotating the carcass during the dehairing operation, and means for actuating said means to eject the carcass from the machine.

40 6. In a dehairing machine of the character described, a plurality of dehairing devices each operating upon the carcass in a circular path, said dehairing devices being mounted in a manner to support said carcass during the dehairing operation, certain of said dehairing devices rotating relatively in opposite directions, means for rotating the carcass during the dehairing operation, and means for actuating said means to eject the carcass from the machine.

55 7. In a dehairing machine of the character described, a plurality of dehairing devices each operating upon the carcass in a circular path, said dehairing devices being mounted in a manner to support said carcass during the dehairing operation, means for rotating the carcass during the dehairing operation, means for actuating said means to eject the carcass from the machine, and means operable during the ejection of a carcass for introducing another carcass within the field of operation of said dehairing devices.

60 8. In a dehairing machine of the character described, a plurality of dehairing de-

vices each operating upon the carcass in a circular path, said dehairing devices being mounted in a manner to support said carcass during the dehairing operation, certain of said dehairing devices rotating relatively in opposite directions, means for rotating the carcass during the dehairing operation, means for actuating said means to eject the carcass from the machine, and means operable during the ejection of a carcass for introducing another carcass within the field of operation of said dehairing device.

9. In a dehairing machine of the character described, a plurality of dehairing devices each operating upon the carcass in a circular path, said dehairing devices being mounted in a manner to support said carcass during the dehairing operation, and means operable simultaneously for discharging a carcass from the machine and introducing another carcass into the machine.

10. In a dehairing machine of the character described, the combination with dehairing devices adapted to support a carcass at their ends, of a conveyer operable to rotate the carcass, and means for actuating said conveyer periodically to discharge the carcass from the machine.

11. In a dehairing machine of the character described the combination with a plurality of dehairing devices, of a cradle adapted to support a carcass and carry it into the field of operation of said dehairing devices, a guide for the cradle and means for actuating said cradle, said means including a series of compound pulleys and an eccentric.

12. A hog dehairing machine having a plurality of dehairing devices having dehairing elements operating in a substantially circular path of contact on the surface of the carcass throughout the entire travel of said dehairing elements, said dehairing devices being mounted so that the carcass rests thereon.

110 13. A hog dehairing machine having a plurality of dehairing devices provided with elements operating in a circular path of contact on the surface of the carcass, the center line of the carcass being in substantial coincidence with the axis of rotation of said dehairing devices, said dehairing devices being mounted so that the carcass rests thereon.

14. A device of the character described comprising a framework, dehairing mechanism mounted thereon, a scalding tank, a curved guideway extending from the tank to the framework and a cradle movable on said guideway for transferring a carcass from the tank to the dehairing mechanism.

125 15. A device of the character described comprising rotatable dehairing devices positioned with their faces at an angle and adapted to support a carcass resting against said faces and an inclined conveyer located

- adjacent said devices and adapted to support and rotate the carcass resting against said faces.
16. A device of the character described comprising two sets of rotatable carcass supporting devices having flat supporting faces positioned at an angle to each other, one of said devices having dehairing elements secured thereto.
17. A device of the character described comprising a rotatable carcass supporting and dehairing member positioned with its active face at an angle to the vertical and an endless chain conveyer adapted to support and rotate the carcass against the face of 15 the member.
18. In a device of the character described comprising a conveyer and a dehairer each positioned at an angle to the other so as to form a V-shaped space between them for receiving a carcass, said conveyer being adapted to rotate the carcass against the dehairer.
- In witness whereof I hereunto subscribe my name this 22nd day of October, A. D. 1918.

CARL F. NAYER.
